UNITED STATES PATENT OFFICE.

JAMES REUBEN ROSE, OF ALLEGHENY, ASSIGNOR OF ONE-HALF TO J. THORPE
POTTS, OF PHILADELPHIA, PENNSYLVANIA.

PROCESS OF MANUFACTURING GAS.

SPECIFICATION forming part of Letters Patent No. 506,078, dated October 3, 1893.

Application filed April 22, 1893. Serial No. 471,384. (No specimens.)

To all whom it may concern:

Be it known that I, JAMES REUBEN ROSE, a citizen of the United States, residing at Allegheny, in the county of Allegheny and State 5 of Pennsylvania, have invented certain new and useful Improvements in Processes of Manufacturing Gas; and I do hereby declare the following to be a full, clear, and exact description of the invention, such as will enable 10 others skilled in the art to which it appertains to make and use the same.

My invention relates to improvements in process for the manufacture of fuel and illuminating gas, and it consists of certain novel 15 features hereinafter described and claimed.

Reference is had to the accompanying drawings, in which corresponding parts are indicated by similar letters throughout the several views.

20 Figure 1 represents a sectional view of the apparatus along the line $x-x$ of Fig. 2, looking to the right, parts being shown in elevation. Fig. 2 represents a section of the apparatus shown in Fig. 1 along the line $y-y$ of the said figure, the pipes connecting the various parts being shown in plan. Fig. 3 represents a section of the device shown in Fig. 4, along the line $x'-x'$ of the said figure, and represents a modification of the apparatus 25 shown in Figs. 1 and 2. Fig. 4 represents a section along the line $y'-y'$ of Fig. 3, the pipes connecting the various parts being shown in plan.

A represents one of a group of generators, 30 in which any combustible fuel is used. A^0 in Figs. 3 and 4 represents a similar generator, there being four of the said generators represented in Figs. 1 and 2, and three in Figs. 3 and 4. The said generators are provided with doors a for cleaning out the lower 35 part of the furnace, apertures a' , grates a^2 , of any desired type, pipes a^3 for admitting steam and air, and devices A' for feeding the fuel into the generator. Poke holes a^3 and 40 covers a^4 , as shown in Fig. 3, may also be provided.

B represents one of a pair, or several pairs of combined generators, regenerators and fixers, provided with a central partition wall b , 45 which divides the interior space into two semi-cylindrical chambers. These chambers

are further divided by perforated arches b' , over which perforated arches, a checker work or filling or refractory material is placed. By means of these arches, the combined generator, regenerator and fixer B is divided into four chambers, B^0 , B' , B^4 and B^5 ; over the checkerwork in the chambers B' and B^4 empty spaces B^2 and B^3 are left as shown in Figs. 1 and 3. These empty spaces or upper chambers B^2 and B^3 are provided with doors b^{14} and b^{15} for putting in the refractory material, and a relief cap b^{16} . The lower chamber B^0 is provided with a vertical wall b^0 a short distance away from the wall b , leaving between 55 the two walls a chamber B^6 provided at its base with an inlet b^{11} for the admission of any hydro-carbon. Each of the lower chambers B^0 and B^5 is provided with doors b^4 and b^5 and corresponding apertures for feeding 60 fuel in on the grates b^3 , and doors b^6 and b^8 , and b^7 and b^9 for cleaning out the bottom of the furnace and the ash pit respectively.

b^{12} and b^{13} are pipes for the admission of steam and air.

D represents a steam superheater provided with steam coil D' .

The generators A in Figs. 1 and 2 are connected by pipes P' to the main pipe P , which is connected to the branch pipe P^2 leading 80 into the two generators B. Pipes P^3 connect the chambers B^0 with the pipes P^4 leading to the steam superheaters D from which the gas is carried by the pipe P^9 to the place of consumption, or to a suitable reservoir.

The generators A^0 shown in Figs. 3 and 4 are connected by the pipes P^5 to the pipe P^6 , opening into the pipes P^7 communicating with the chambers B' ; these various pipes are provided with valves p , by which the generators 90 may be cut out entirely, or the route of the gases may be changed, as will be hereinafter described.

The various generators A and A^0 are provided with relief caps P^8 which may be of 95 any well known construction.

The operation of the device is as follows:— The generators A or A^0 and the chambers B^0 are charged with coal or any fuel containing carbon, and the regenerators B^5 are charged with 100 coke or hard coal. This fuel is ignited and is blasted to incandescence. The products of

combustion from B⁰ and B⁵ pass up through the checker brick in B' and B⁴, heating them, and thence into the air by means of the relief cap b¹⁶; the products of combustion from the 5 fuel in generators A escape into the air by means of the relief cap P⁸. This heating and allowing the products of combustion to escape into the air is only done on the initial heating up. As soon as the machine is closed 10 up and the proper outlet for the escape of the gases opened, the manufacture of gas is continuous hour by hour, day by day,—only one generator at a time being detached for the purpose of cleaning. Steam for the 15 purpose of obtaining hydrogen and air for the purpose of supporting combustion, are admitted through the pipe a⁵; at the bottom of the generators A⁰,—and the resultant gases rising from above the incandescent fuel pass 20 through the pipes connected to the generator and enter one of the chambers B⁰. Entering this chamber above the fuel on the grate b', the gases mix with the hydro-carbon gases coming from the chamber B⁶ and the gases 25 arising from the fuel in B⁰, and the mixture passing up through the perforated arch and highly heated refractory material B', over the top of the walls B down through the refractory material in B⁴ into the chamber B⁵. Thence, 30 passing out through the pipe P³, it reaches the steam superheater D, whence, by means of the pipe P⁹ it is carried to the place of consumption. The gases from the generators A⁰ and that 35 retort B in process of being heated up pass over the incandescent fuel in the chamber B⁰ and have part of their carbon di-oxide reconverted into monoxide; while in passing through the heated refractory material in the chambers B' and B⁴, the resultant gases become fixed. Then after leaving the chamber 40 B⁴ the gases which are enriched by the hydrocarbon injected through the chamber B⁵ pass over the incandescent coke in the chamber B⁵ and most of the remaining carbon dioxide present is converted into carbon monoxide. A pressure is maintained in the machine which does not permit of a suction of 45 the gas from the regenerator. Hence the gas churns in every body of fuel and cannot escape without contact. Thence the gases go 50 to the steam superheater where the hot gases super-heat the steam used in the apparatus, which steam passes through the coil D', and is conducted to the various generators by 55 pipes, not shown. Each of the various generators being supplied with its own valve or valves, may be cut out from the apparatus, for purposes of cleaning or repairing, or for any other cause, without interfering with the 60 continuous operation of the apparatus. Since the passage of steam through the generator and regenerator B will tend to bring down its temperature and since a high heat is required in fixing the gases, the generators B are preferably worked in pairs, one of each pair being used for regenerating and fixing the gases 65 while the other is being heated up, and the

products of combustion and the gases arising therefrom are mixed with the other gases from other generators. After passing the gases for 70 a given time through one generator B, the course of the gases is reversed by means of the admission valves, and the gas is then regenerated and fixed in the other generator and regenerator of the pair; while in the regenerating and fixing chamber which has just been running, air is admitted at the bottom and it is heated again for the next run.

In the process of heating up, the products of combustion from the regenerator B⁵ are 80 carried up through the refractory material in the chamber B⁴, over the wall b, down through the refractory material in the chamber B⁷ and through the perforated arch b', where they meet with the gases from the generator B⁰; and hydro-carbon gas from the chamber B⁶. Thence they pass to the pipe 85 leading to the other generator B, in which pipe the said products of combustion mingle with the gases from the various generators 90 and the mixture enters the regenerating and fixing chamber, where the process of regeneration and fixing is carried out.

The gases from the generators A and B⁰ are producer gases. When they meet with hydro-carbon gas and become fixed in B', B⁴ and B⁵ they are hydro-carbon gases of approximately the following composition:—Hydrogen, ten per cent.; marsh gas, six per cent.; carbon monoxide, twenty per cent.; heavy hydro-carbons, six per cent.; carbon, dioxide 0.99 per cent.; oxygen, .54 per cent.; nitrogen, 54.47 per cent.

When the regenerator which is being heated up has reached the desired temperature, the 105 heating up is stopped, and the gases to be regenerated and fixed are made to pass through that generator. By this process a continuous flow of gas is maintained. Should the generators B get too hot, steam may be introduced through the pipes b¹² and b¹³ which will bring down the temperature sufficiently. The air is supplied by a pressure, as also the steam.

It will be evident that by increasing the 115 amount of steam introduced into the base of the generators A, the quantity of hydrogen set free may be increased, and hence better fuel gas may be obtained; while by increasing the percentage of carbon, either by diminishing the amount of steam admitted, or by injecting a greater amount of hydro-carbon through the pipe at the base of the chamber B⁶, an illuminating gas richer in carbon 120 may be obtained. It will be seen that in this process a mixture of gases containing olefiant gas is carried from the various generators to a large pipe where the temperature is reduced and free hydrogen and carbon are evolved; then conducting this mixture into a highly 125 heated chamber the carbon and hydrogen unite again to form marsh gas, and the carbon dioxide present is reduced to monoxide, whereby great heating effect is obtained.

It will be noted that the regenerating and fixing is done in the same retort B, which is heated internally by the fuel used in making the gas.

5 Having thus described my invention, what I claim, and desire to secure by Letters Patent of the United States, is—

The process for the manufacture of fuel or illuminating gas which consists in passing steam and air through a mass of highly heated fuel, then passing these gases over a bed of incandescent carbon and intermingling with the said gases a highly heated hydrocarbon

gas, then passing the resulting mixture of gases through highly heated fixing chambers, 15 and finally passing the fixed gases above a layer of coke or coal heated to a high temperature, substantially as and for the purposes described.

In testimony whereof I affix my signature in 20 presence of two witnesses.

JAMES REUBEN ROSE.
